UNITED STATES PATENT OFFICE

RICHARD M. DUGDALE, OF DEDHAM, MASSACHUSETTS, ASSIGNOR TO FARRINGTON MANUFACTURING COMPANY, OF BOSTON, MASSACHUSETTS, A CORPORATION OF MASSACHUSETTS

PRINTING DEVICE

Application filed May 2, 1929. Serial No. 359,816.

This invention relates to a device for printing names and addresses or other indicia on sales slips or the like and has for its principal objects the provision of a device 5 for use by department stores and other establishments which avoids the many mistakes ordinarily resulting from illegible and inaccurate writing of names and addresses by sales clerks, which facilitates identification 10 of charge customers by the use of a printing plate carried by the customer for printing the sales slips, which avoids all tendency to soil the printing plate with ink in the printing process so that the plate may be freely 15 handled and carried in a purse without soiling the hands or purse contents, which clearly and sharply prints any reasonable number of carbon copies, which requires little effort in manipulation so that it may 20 be used by sales girls with facility, which is sufficiently light and compact to be readily portable if desired, which may be arranged to open automatically for the insertion of the printing plate and sales slips or the like 25 in the normal and natural manner of lifting the device by the operating handle, which may be used with ink sheets of either the ribbon type or carbon sheet type, which facilitates the insertion of the printing plate, 30 which permits the use of a printing plate having the indicia in non-reversed order for ready reading, and which is generally superior to prior devices for similar uses.

For the purpose of illustrating the genus 35 of the invention, typical embodiments are shown in the accompanying drawings in which,

Fig. 1 is a front elevation with parts in 40 section;

Fig. 2 is a section on line 2—2 of Fig. 1;

Fig. 3 is a rear elevation with portions 45 broken away;

Fig. 4 is a plan view of the printing plate;

Fig. 5 is a section on line 5—5 of Fig. 4;

Fig. 6 is a front elevation of a modification 50 with parts broken away;

Fig. 7 is a section on line 7—7 of Fig. 6;

Fig. 8 is a section on line 8—8 of Fig. 6;

Fig. 9 is a detailed sectional view;

Fig. 10 is a section on line 10—10 of Fig. 9; and

Fig. 11 comprises two views of one of the ribbon reels.

The particular embodiment of the invention shown in Figs. 1 to 5, and 9 to 11 inclusive, comprises a casing 1 having its lower end open, a plate holder 2 pivoted to the casing at 3 to swing from the closed position shown in Fig. 1 to an open position such as shown in Fig. 6, an inner casing 4 welded or otherwise mounted on the inner face of the back of the outer casing 1 and having two integral flanges 5 extending forwardly at right angles to serve as ribbon guides, the upper and lower ends of these flanges being bent inwardly as shown in Fig. 1, a horizontal guide bar 6 welded or otherwise mounted on the flanges 5 and/or the back of the casing 4, a roller carriage 7 which is U-shaped in cross section, as shown in Fig. 2, and which has a longitudinal opening to receive guide 6, rollers 8 journaled in the depending flanges 9 of the carriage, a cam 10 extending upwardly from the top of the carriage 7, a spring 11 yielding urging the carriage to the right (Fig. 1) and actuating mechanism cooperating with the cam 10 to move the carriage to the left against the action of the spring 11.

The particular actuating mechanism illustrated in Figs. 1, 2 and 3 comprises a plunger 12 sliding in a tubular extension 13 extending upwardly from the casing 1, a cam roller 14 journaled in the lower end of the plunger 12 in cooperative relationship with the cam 10, a pin 15 fast in the extension 13 and extending through a slot in the plunger 12, a second plunger 16 sliding in a guideway in extension 13 parallel to the guideway of the plunger 12, a pin 17 interlocking the two plungers together and a spring 18 normally holding the plungers in uppermost position.

When using an ink ribbon the preferred mechanism for supporting the ribbon is illustrated in Figs. 1, 9, 10 and 11. This mechanism comprises two stud shafts 19 rigidly mounted on the backs of the casings 1 and 4 by means of screws 20 with shoulders 21 spaced from the back of the inner casing

4 loosely to receive a ratchet wheel 22 and a spacing washer 23. The ratchet wheel 22 has pins 24 projecting forwardly therefrom immediately outside the periphery of the flange 21 on the shaft 19. The inner casing 4 is provided with a recess 25 immediately below each of the reel supports and a spring 26 is mounted on the inner casing 4, by means of struck-up ears 35 (Fig. 9), to extend into the recess 25 and bear against the spacing washer 23 frictionally to retard rotation of the ratchet wheel 22 around the shaft 19. The forward ends of the shafts 19 are provided with grooves 27 to interlock with bayonet slots 28 on the front cover 29, so that the ribbon reels are held on the shafts 19 by the front cover 29 when the cover is applied to the casing 1 as shown in Fig. 6.

The ribbon reels are preferably constructed as shown in Fig. 11, comprising a tubular part 30 having radial flanges 31 and 32 at the opposite ends, the rear flanges 32 having teeth 33 struck rearwardly therefrom to interengage with the pins 24 on the ratchet wheels. As shown in Fig. 3 the ratchet wheels have their teeth reversed with respect to each other so that the ribbon 34 is fed in one direction across the bottom of the casing 1 when one ratchet wheel is rotated, and in the reverse direction when the other ratchet wheel is actuated. The preferred mechanism for actuating the ribbon reels is shown in Figs. 1, 2 and 3 and comprises pawl means in the form of a tumbler 36 pivotally mounted on the lower end of plunger 12 by the same pin 37 which supports the cam follower 14. Pivotally mounted on the back of the tumbler are two pawls 38 for actuating the two ribbon reels respectively. Pivotally mounted on the forward face of the tumbler 36 are two rollers 39 for engagement with the periphery of rolls of ribbon on the two reels respectively. The tumbler 36 is movable from a central position to either of two operative positions in which the pawls 38 cooperate with the ratchets 22 respectively. A spring 40 is mounted on the inside of the inner case 4 in cooperative relationship with a lug 41 on the tumbler 36 to snap the tumbler from the central position into either of its operative positions and yieldingly to hold it in either of the latter positions. As shown in Fig. 1, the tumbler is in the right-hand operative position (left-hand position when viewed from the rear as in Fig. 3) to actuate the right-hand ribbon reel, the right-hand pawl 38 engaging the right-hand ratchet 22 to feed the ribbon one step to the right each time the plungers 12 and 16 are returned to raised position by the springs 11 and 18. When the roll of ribbon on the actuated reel reaches a predetermined diameter, it moves the adjacent roller 39 sufficiently to snap the tumbler into the other operative position,

whereupon the feed of the ribbon is reversed.

While any one of a great variety of printing plates may be employed with this device, a suitable form comprises a pressed metal plate P, such as shown in Figs. 4 and 5, which has the indicia embossed in its central raised portion. This plate fits into a recess in the upper side of the plate holder 2 and may either rest in the recess by gravity or be held by a friction or positive catch. As shown in the figures, the rear edge of the plate frictionally engages in a groove 42 at the rear of the recess.

The modification shown in Figs. 6, 7 and 8 is similar to that shown in the remaining figures except in two respects. In the first place, the plunger 12' is actuated by a lever 43 pivoted in the upper end of the plunger at 44, and having its short end pivotally interconnected with the casing by a link 45. In the second place each of the rollers 8' are journalled in a separate U-shaped support 46, which extends over a block 47 having a recess to receive the guide plate 6'. The sides of the block 47 are milled to provide grooves for the depending portions of the U-shaped supports 46, to permit vertical movement of the rollers and supports relative to the block 47. A rubber block 48 is provided above the horizontal portion of each roller support. A plate 49 extends across the top of the rubber blocks and is secured to the block 47 by means of screws as shown at 50 in Fig. 6. The cam 10' is mounted on the top plate 49. Thus each roller is independently movable in a vertical direction and is yieldingly held in the lowermost position (in Figs. 6 and 8) by means of its rubber block 48, whereby the rollers may individually adjust themselves to slight irregularities in the printing plate.

In use the plate holder automatically moves to the open position shown in Fig. 6 when the device is lifted by the handle, the handle preferably being located as shown in Figs. 1 and 6 so that the plate holder will extend substantially horizontally when the device is loosely upheld by the handle. The printing plate is then slipped into the recess in the plate holder with its rear edge extending into the groove 42' where it is frictionally held in position due to the resiliency of the sheet metal plate. Sale slips or other sheets to be printed are then positioned over the printing plate, which is rested on a table or other suitable support, and the casing is then swung downwardly to the closed position, shown in Fig. 1. The printing is then effected by depressing the handle to cause the rollers to move back and forth across the sheets. Ordinarily one complete reciprocation back and forth is sufficient so that the closing of the space between the casing and plate holder, the movement of the car-

riage back and forth and the opening movement of the casing can be effected by a single continuous downward and upward movement of the handle. The downward movement of the handle not only serves to reciprocate the carriage but also forces the pressure means (the rollers in the illustration) and the impression means (the printing plate) together to compress the sheets 5 therebetween. Inasmuch as the sales slips are ordinarily attached at their upper ends to a pad holder, the plate holder 2 is preferably rounded at its left-hand end as shown in Fig. 7 so that it may readily be inserted 10 under the sheets to be printed by lifting these sheets slightly from the remaining sheets of the pad.

It will, of course, be understood that the uppermost sheet is printed by the ink ribbon 20 34 and that any number of underlying sheets may be printed by inserting carbon sheets therebetween in the usual manner. By locating the printing plate on the side of the sheets opposite the ink ribbon, the plate contacts with neither ink ribbon nor carbon sheets, and is therefore not soiled in use, so 25 that it may be handled and carried in a purse without danger of soiling the hands or purse contents.

30 From the foregoing it will be evident that the unique relationship between the plate holder and the pressure means not only avoids soiling the plate with either ink ribbon or carbon paper but also facilitates 35 the insertion and removal of the printing plate. By using roller pressure means the impression is sharp and clear, even with a considerable number of carbon copies; and in this connection I have found rollers of 40 hard fiber composition to be superior, although bakelite and other materials are suitable for many purposes.

From the foregoing it will be evident that the printing pressure is approximately proportional to the resistance of springs 11 and 45 18 and is largely independent of the pressure applied to the handle inasmuch as the downward pressure between the rollers and printing plate increases until the force applied to the handle is sufficient to overcome 50 the resistance of the springs, whereupon the rollers start to roll over the slips, thereby preventing the printing pressure from further increasing. Thus excessive force applied to the handle merely results in quicker 55 movement of the rollers across the slips without damaging the printing plate or causing the raised letters to cut through the 60 slips. This action may be more readily apparent when it is considered that if the 65 springs be removed the slightest downward pressure on the handle would move the rollers across the slips without any substantial component of force downward to compress

the slips between the rollers and printing plate.

I claim:

1. In a device for printing names and addresses or other indicia on sales slips or the like, the combination of opposed impression means and pressure means movable apart for the insertion of sheets therebetween, the impression means having thereon indicia arranged in non-reversed order so that each slip may have the indicia printed thereon from an ink sheet on the side of the slip opposite the impression means, said pressure means comprising a roller, and means for moving the roller laterally over the sheets progressively to press the latter against each other and the impression means under the influence of rolling pressure. 70

2. A device for printing names and addresses or other indicia on sales slips or the like comprising a casing having an open end and a printing plate holder associated therewith, the parts having relative movement to permit the insertion and removal of sheets therebetween, means in the casing for feeding an ink ribbon across said open end, and pressure means including a roller in the casing for pressing a portion of said ribbon against the face of a sheet inserted between the open end and the plate holder, 85 whereby the indicia on the printing plate may be reproduced on the sheet without direct contact between the plate and the ribbon. 90

3. A device for printing names and addresses or other indicia on sales slips or the like comprising a casing having an opening therein, a plate holder pivoted to the casing to present a printing plate to said opening, and pressure means in the casing for pressing sheets against said plate. 100

4. A device for printing names and addresses or other indicia on sales slips or the like comprising a casing having an opening therein, a plate holder pivoted to the casing to present a printing plate to said opening, reciprocating means including a roller in the casing for compressing sheets against said plate, and means for automatically feeding an ink ribbon across the opening in front 110 of the roller. 115

5. A device for printing names and addresses or other indicia on sales slips or the like comprising a printing plate holder, a roller for progressively pressing successive portions of a sheet against the printing plate, said roller being movable along a path parallel to the plate, and means for moving the roller along said path including an actuator movable transversely of said 120 path. 125

6. A device for printing names and addresses or other indicia on sales slips or the like comprising a printing plate holder, a roller movable along the plate holder for 130

progressively pressing successive portions of the slips against the printing plate, and means for conjointly moving the roller and compressing the slips between the plate holder and roller, including a spring for moving the roller in one direction and an actuator for moving the roller in the other direction against the action of the spring, the actuator advancing in a direction to force the roller toward the printing plate.

7. A device for printing names and addresses or the like on sales slips or the like comprising a base, a superposed head, means on the base for detachably holding a separable printing plate in printing position relatively to the head, the head being movable from the base to afford an unobstructed view of the plate when in printing position and in the absence of a superposed sales slip, and to permit the insertion of sail slips over the plate with an ink sheet between the slips and head, and means on the head for pressing the slips against the plate when the head is moved back to printing position.

8. The method of printing names and addresses on sales slips and the like with identification plates carried by customers, which comprises pressing the plates against the back of the sheets to be printed and comitantly pressing inked material against the front of the sheets, whereby the indicia on the plates may be in non-reversed order for ready reading and is reproduced on the sheets without inking the plates.

9. A device for printing names and addresses or the like on sales slips or the like with separable identification plates, comprising a base and a movable head, the base having its surface facing the head unobstructed when the head is moved away and shaped to interfit with the plates so as to hold a plate in printing position without attaching the plate to the base, and means on the head for pressing the slips against the plate.

10. A device for printing names and addresses or the like on sales slips or the like with separable identification plates, comprising a base, a head movably mounted thereon, the base including means for detachably retaining an identification plate during printing, means movable relatively to the head for pressing slips against the plate when so positioned, and a handle for successively moving the head toward the base and then actuating said means in one continuous movement in the same general direction.

11. A device for printing names and addresses or the like on sales slips or the like with separable identification plates, comprising a base, a head movably mounted thereon, the base having its surface facing the head shaped to interfit with the plates so as to hold a plate in printing position without attaching the plate to the base, a roller

movable relatively to the head for progressively pressing successive portions of slips against the plate when so positioned, and a handle for successively moving the head toward the base and then actuating said roller in one continuous movement in the same general direction.

12. A device for printing names and addresses or the like on sales slips or the like with separable identification plates, comprising a base, a head movably mounted thereon, the base including means for detachably retaining an identification plate during printing, pressure means carried by the head for progressively pressing successive portions of sheets to be printed against a plate when so positioned, and means including a handle for successively moving the head toward the base and then actuating said pressure means by one continuous movement of the handle in one general direction.

13. A device for printing names and addresses or the like on sales slips or the like with separable identification plates, comprising a base including means for detachably retaining an identification plate during printing, a head connected to said base for swinging toward said base to a printing position and away from said base to permit a sheet to be superposed on an identification plate, pressure means carried by the head and movable relatively thereto for said sheet against the plate, and means including a handle for successively moving the head toward the base and then actuating said pressure means by one continuous movement of the handle in one general direction.

14. A device for printing names and addresses or other indicia on sales slips or the like, comprising a printing plate holder, a roller for progressively pressing successive portions of a sheet against the printing plate, said roller being movable along a path parallel to the plate, and means for moving said roller along said path including a plunger movable transversely of said path.

15. A device for printing names and addresses or other indicia on sales slips or the like, comprising a plate holder for detachably retaining an identification plate, a movable head pivotally associated with said plate holder, and pressure means carried by said head and movable transversely of said head for pressing sheets against said plates.

16. A device for printing names and addresses or the like on sales slips or the like with separable identification plates, comprising a plate holder for such plates, a head movably associated therewith, a roller carried by said head for progressively pressing successive portions of slips against a plate retained by said plate holder, a roller-moving member associated with said roller for moving the same, a plunger movable trans-

versely to the path of the roller, cam mechanism for transmitting movement of said plunger to said roller-moving member, and a handle lever engageable with said head and said plunger for actuating said plunger.

17. A device for printing upon sales slips or the like with identification plates of the type suitable to be carried by customers and bearing indicia such as the customer's name and address in raised letters disposed over a substantial area thereof, comprising means for detachably retaining such a plate in position for its raised letters to print through a superposed sales slip to the opposite side thereof, means for applying ink to the side of said sales slip opposite to the plate, and means for pressing the sales slip against the plate throughout said area without substantial movement of the slip in the direction of its length during printing and for simultaneously pressing the ink applying means against the sales slip, thereby to print upon the side of the sales slip opposite to the plate.

18. A device for printing upon sales slips or the like with identification plates of the type suitable to be carried by customers and bearing indicia such as the customer's name and address in raised letters disposed over a substantial area thereof, comprising means for detachably retaining such a plate in position for its raised letters to print through a superposed sales slip to the opposite side thereof, means for applying ink to the side of said sales slip opposite to the plate, and means for applying rolling pressure to the sales slip and plate over said area occupied by said raised letters without substantial movement of the slip in the direction of its length during printing and for simultaneously pressing the ink applying means against the sales slip, thereby to print upon the side of the sales slip opposite to the plate.

19. In a device for printing names and addresses or other indicia on sales slips or the like, of the type having a space for the insertion of sheets to be printed, impression means on one side of the space, said impression means comprising a removable plate having lines of raised letters disposed substantially in a plane, and an ink sheet and pressure means on the other side of the space, the pressure means comprising a roller, and means for rolling the roller over the sheets progressively to press the latter against each other and the impression means.

20. In a device for printing names and addresses or other indicia on sales slips or the like, of the type having a space for the insertion of sheets to be printed, impression means on one side of the space, said impression means comprising a generally flat printing plate suitable to be carried by a customer, and an ink sheet and pressure means

on the other side of the space, the pressure means comprising a roller, and means for rolling the roller over the sheets progressively to press the latter against each other and the impression means.

21. A device for printing names and addresses or the like on sales slips or the like with separable identification plates, comprising a base detachably to receive one of said plates, a head mounted on the base to permit the insertion of said slips therebetween, pressure means movably mounted on the head to press the slips against said plate, a handle for actuating said means, and means for controlling the pressure so that the printing pressure is largely independent of the force applied to the handle.

22. A device for printing names and addresses or the like on sales slips or the like with separable identification plates, comprising a base detachably to receive one of said plates, a head movably mounted on the base to permit the insertion of said slips therebetween when the head is moved away from the base, pressure means movably mounted on the head to press the slips against said plate, a handle for moving the head toward the base and actuating said pressure means in one continuous movement in the same general direction, and a spring arranged to resist said movement during actuation of the pressure means so that the printing pressure is approximately proportional to the resistance of the spring and largely independent of the force applied to the handle.

23. A device for printing names and addresses or other indicia on sales slips or the like comprising a casing having an opening therein, a plate holder pivoted to the casing to present a printing plate to said opening, a pressure member in the casing and movable across the opening for compressing sheets against said plate, and means for automatically feeding an ink ribbon across the opening in front of the pressure member.

Signed by me at Boston, Massachusetts,
this first day of May, 1929.

RICHARD M. DUGDALE.
